WINDING CORE SUPPORT

Ernest K. Bauer, Meadville, Pa., assignor to
 American Viscose Corporation, Wilmington,
 Del., a corporation of Delaware

Application November 13, 1950, Serial No. 195,314

6 Claims. (Cl. 242—130)

1

This invention relates to a system for supporting a winding core in a winding machine of the type which comprises a driving roll or cylinder against which the winding core is urged during winding.

The principal object of the present invention is to provide a support for the winding core in this type of winding machine which is simple and compact in construction, is adapted to exert continuous pressure between the core and the driving roll throughout the building of the package, and in which the core is readily replaced in preparation for the winding of the next package. These and other objects and advantages of the invention will be apparent from the drawing and the description thereof hereinafter.

In the drawing,

Figure 1 is an end elevation of a single winding core supporting unit which comprises a part of a multiple winding machine constructed in accordance with the present invention;

Figure 2 is a sectional view as seen at II—II of Figure 1 showing in addition parts of adjoining units;

Figure 3 shows the movable core supporting structure of Figure 2; and

Figure 4 is a detail section taken on line IV—IV of Figure 3.

As shown in Figure 1, the winding machine comprises a driving roll or cylinder 3 which is positively rotated about its axis and against the periphery of which the winding core or carrier 4 bears. A traverse guide 5 carried on the reciprocable traverse bar or rail 6 serves to guide the thread into the nip between the driving roll and the core or the winding thereon. A fixed rail 7 extends horizontally the length of the machine above and toward the back of the driving roll 3. The rail 7 carries at spaced intervals along its length a number of brackets 8, the base portions 9 of which are bolted to the rail 7 by means of the bolts 10 and the nuts 11. Each of the brackets comprises two upwardly projecting arms 12 and 12a. The arm 12 comprises two parts. One part 13 is upright and integral with the base 9 from which it extends at right angles and comprises a laterally extending semi-cylindrical boss 14 having a semi-cylindrical bore 15. This part 13 of the arm terminates in a horizontal plane and has secured to it a part 16 provided with a semi-cylindrical boss 17 and a semi-cylindrical bore 18 which mate with the corresponding boss and bore of the part 13 to provide a horizontal split bearing for the rods or shafts 19. The part 16 is secured to the

2

part 13 by cap screw 20 and in the lower part of its outer end, it is provided with a recess or bore 21 which is adapted to receive a solid or hollow button, plug or cup 22 axially slidably mounted therein and a spring 23 for urging the button outwardly from the recess. The button 22 has an externally facing base, which is preferably flat and is adapted to frictionally rub against one face of the arm 24 of the core-supporting bracket. The arm 12a extends upwardly and is provided with a cylindrical bore or recess 25 containing a button 26 which is urged outwardly from the recess by a spring 27 therein. The disposition of the bore 25 in arm 12a is preferably in alignment with the bore 21 in arm 12 so that buttons 22 and 26 are urged against opposite faces of the arm 24. As shown, the contiguous friction surfaces of buttons 22 and 26 and of arm 24 lie in parallel planes perpendicular to the axis of rods 19.

The core holder or support proper comprises the rod or shaft 19 mentioned hereinabove to which an arm 24 and a hinge member or bracket 28 are secured adjacent the opposite ends thereof, such as by means of taper pins 29 and 30 respectively. The arm 24 is integral with the sleeve 24a which fits about the rod 19 and the hinge bracket 28 has a similar sleeve 28a which fits about the rod 19. The sleeves 24a and 28a are spaced from the ends of the rod or shaft 19 so that the ends of the rod project a short distance into the split bearings (comprising bores 15) of adjacent arms 12. They may project into such bores any distance but, as shown, each end projects slightly less than half way thereto to leave a corresponding portion of the bore available for the projection thereinto of the adjacent rod 19 of adjacent core holders. The sleeves 24a and 28a abut against the ends of the split bearings, with the interposition of a washer or washers, such as 41, if desired, and they thereby prevent axial movement of the rod 19.

The hinge bracket 28 has a laterally projecting lug 31 bored to receive a pintle 32. A yoke 33 has a bifurcated portion complementary to, and adapted to embrace, the lug 31. This bifurcated portion is provided with aligned bores to receive the pintle 32. The yoke 33 carries fixedly secured thereto an outwardly extending arm 34. A spring 35 extended between a pin 36 on the sleeve 28a and a pin 37 on the yoke 33 urges the yoke in a clockwise direction as viewed in Figure 3. The arms 24 and 34 are provided with rotatable trunnions 38 and 39 respectively

adapted to fit within a cylindrical core or yarn carrier. The arm 34 may have an offset terminal portion or extension 40 to serve as a handle.

The trunnions are preferably provided with an elastic band 38a, such as of rubber, in a recess 39a adjacent the flange 39b. The band may be of round or any other section including the generally trapezoidal section shown, and serves to bind or grip the edge of the core 4 and the yarn when the starting end of the latter is inserted between the trunnion and the core 4 at the beginning of winding. Each trunnion is preferably provided with an annular recess 39c. A ring 39d having a tapered or conical outer periphery 39e is secured to the respective one of the arms 24 or 34 and extends partially into the recess as shown for the purpose of preventing a loose thread or yarn end from entering the bearing. Instead, such a loose end will merely slide off. An additional means to hold or grip the yarn end to facilitate starting may be provided in the form of the annular brush 39f secured concentrically by the hub rivet 39g. In use, the thread end may be held across the entire diameter either of the end of core 4 or of the trunnion, and when the core is pushed on the trunnion, the thread is pushed into the brush.

In operation, an empty core 4 is mounted upon the trunnions 38 and 39, which mounting is facilitated by the swinging of the arm 34 (by manual engagement of handle 40) in a counter-clockwise direction as viewed in Figures 2 and 3 until the core is placed upon the trunnion 38 after which arm 34 may be released to allow the trunnion 39 to enter the other end of the core. Then the mounted core is swung into engagement with the driving roll 3 against the frictional resistance of the buttons 22 and 26 bearing against the arm 24. During winding, as the convolutions build up about the core, the package gradually swings upwardly about the axis of shaft 19. The friction buttons 22 and 26 snub against the arm 24 and resist, restrain, or retard this upward swinging with a force dependent upon (1) the coefficient of friction between the surfaces of the arm 24 and the buttons 22 and 26 and (2) the pressure exerted by the springs 23 and 27.

The winding core 4 is suspended to the right of the shaft 19 as viewed in Figure 1 and its axis swings through a relatively small arc from the empty position to full position. The control of up and down bouncing due to unround tubes is effected by snubbers 22 and 26. Best results are obtained when the friction of buttons 22 and 26 is so great that it will keep arm 24 in mid-air even with a full winding core if arm 24 is lifted up so that tube 4 is not touching roll 3. This can be assured by proper selection of the materials used in making the snubbing buttons 22 and 26 and by controlling the force exerted thereon by springs 23 and 37. Because of the continuous pressure exerted upon the package windings throughout the winding, the package obtained is well-shaped. It may be made of any desired density by predetermined the resistance which the snubbing buttons exert against the swinging of the package holder about the axis of rod 19. The core supporting unit is extremely simple and compact and is formed of relatively few inexpensive parts. It is also constructed in such a manner that the wound packages can be readily replaced with empty cores. Furthermore, the entire core holder unit may be dismantled in a

very simple manner merely by removing the cap screw 20.

It is to be understood that changes and variations may be made without departing from the spirit and scope of the invention as defined in the appended claims.

I claim:

1. A winding core support for a winding machine in which the winding periphery is driven by direct contact with a driving surface comprising spaced stationary brackets, each having a pair of outwardly projecting arms fixedly carried thereon, a rod rotatably mounted on its axis in an adjacent pair of said brackets, a movable arm rigidly attached to the rod adjacent one end thereof and extending outwardly between the arms of one of the brackets, friction means on one of the bracket arms having a friction surface lying in a plane perpendicular to the axis 10 of the rod for engaging an opposed contiguous surface of the movable arm and for restraining its movement, a hinge member fixed on the rod adjacent its other end, a movable arm hingedly mounted on the hinge member about an axis at 20 right angles to the axis of the rod, spring means for urging the hingedly mounted arm toward the first-mentioned movable arm, and opposed trunnions rotatably carried on the movable arms.

2. A winding core support for a winding machine in which the winding periphery is driven by direct contact with a driving surface comprising spaced stationary brackets, each having a pair of outwardly projecting arms fixedly carried thereon, a rod rotatably mounted on its axis in an adjacent pair of said brackets, a movable arm rigidly attached to the rod adjacent one end thereof and extending outwardly between the arms of one of the brackets, friction means on the bracket arms having friction surfaces lying in planes perpendicular to the axis of the rod for engaging opposite contiguous surfaces of the movable arm and for restraining its movement, a hinge member fixed on the rod adjacent its other end, a movable arm hingedly mounted on the hinge member about an axis at right angles to the axis of the rod, spring means for urging the hingedly mounted arm toward the first-mentioned movable arm, and opposed trunnions rotatably carried on the movable arms.

3. A winding core support for a winding machine in which the winding periphery is driven by direct contact with a driving surface comprising spaced stationary brackets, each having a pair of outwardly projecting arms fixedly carried thereon, a rod rotatably mounted on its axis in an adjacent pair of said brackets, a movable arm rigidly attached to the rod adjacent one end thereof and extending outwardly between the arms of one of the brackets, a recess 30 in each bracket arm, said recess having an opening facing toward the movable arm, a friction element movable in each recess and spring means in each recess for urging the friction element outwardly of the recess against the movable arm for restraining its movement, a hinge member fixed on the rod adjacent its other end, a movable arm hingedly mounted on the hinge member about an axis at right angles to the axis of the rod, spring means for urging the hingedly 40 mounted arm toward the first-mentioned movable arm, and opposed trunnions rotatably carried on the movable arms.

4. A winding core support for a winding machine in which the winding periphery is driven by 50 direct contact with a driving surface comprising

ing spaced stationary brackets, each having a pair of outwardly projecting arms fixedly carried thereon, a rod rotatably mounted on its axis in an adjacent pair of said brackets, a movable arm rigidly attached to the rod adjacent one end thereof and extending outwardly between the arms of one of the brackets, friction means on the bracket arms for engaging opposite surfaces of the movable arm and for restraining its movement, a hinge member fixed on the rod adjacent its other end, a movable arm hingedly mounted on the hinge member about an axis at right angles to the axis of the rod, spring means for urging the hingedly mounted arm toward the first-mentioned movable arm, opposed trunnions rotatably carried on the movable arms, said friction means comprising friction elements in alignment and having flat friction surfaces in engagement with the movable arm therebetween.

5. A winding core support for a winding machine in which the winding periphery is driven by direct contact with a driving surface comprising spaced stationary brackets, each having a pair of outwardly projecting arms fixedly carried thereon, a rod rotatably mounted on its axis in an adjacent pair of said brackets, a movable arm rigidly attached to the rod adjacent one end thereof and extending outwardly between the arms of one of the brackets, friction means on the bracket arms for engaging opposite surfaces of the movable arm and for restraining its movement, a hinge member fixed on the rod adjacent its other end, a movable arm hingedly mounted on the hinge member about an axis at right angles to the axis of the rod, spring means for urging the hingedly mounted arm toward the first-mentioned movable arm, opposed trunnions rotatably carried on the movable arms, each trunnion being provided with an annular recess on its face which is outside the core during winding, and an annular ring having a tapered or conical radially outer surface secured to the respective arm

carrying the trunnion, said ring extending partially into said recess.

6. A winding core support for a winding machine in which the winding periphery is driven by direct contact with the driving surface comprising spaced stationary brackets, each having a pair of outwardly projecting arms fixedly carried thereon, a rod rotatably mounted on its axis in an adjacent pair of said brackets, a movable arm rigidly attached to the rod adjacent one end thereof and extending outwardly between the arms of one of the brackets, a hinge member fixed on the rod adjacent its other end, a movable arm hingedly mounted on the hinge member about an axis at right angles to the axis of the rod, opposed trunnions rotatably carried on the movable arms, an annular friction face on each of said trunnions for frictionally engaging and holding a winding core between said trunnions, means including a brush secured to the inside face of one of said trunnions for resiliently retaining a yarn end passing between one end of the winding core and one of the said annular friction faces, and spring means for urging the hingedly mounted arm toward the first-mentioned movable arm to compress the winding core and said yarn end between the friction faces on the trunnions.
